UNITED STATES PATENT OFFICE

155,686

DESIGN FOR A LIQUID COOLER

William L. Currie, Muskegon, Mich.

Application July 8, 1947, Serial No. 140,151

Term of patent 14 years

(Cl. D67—4)

To all whom it may concern:

Be it known that I, William L. Currie, a citizen of the United States of America, and a resident of Muskegon in the county of Muskegon and State of Michigan, have invented a certain new, original, and ornamental Design for a Liquid Cooler, of which the following is a specification, reference being made to the accompanying drawing, forming a part thereof, in which:

Fig. 1 is a front elevational view of a liquid cooler showing my new design;

Fig. 2 is a top plan view of the liquid cooler depicted in Fig. 1; and

Fig. 3 is a side elevational view of the liquid cooler depicted in Fig. 1.

The essential features of my new design reside in the portions shown in full lines on the drawing.

I claim:

The ornamental design for a liquid cooler, as shown and described.

WILLIAM L. CURRIE.
